United States Patent Office

Des. 214,957
Patented Aug. 12, 1969

214,957

VIEWER

Tom O. Gulliford, Rockford, and George W. Bicknell, Marshall, Mich., assignors to The Worden Company, Holland, Mich., a corporation of Michigan

Filed Jan. 12, 1968, Ser. No. 10,139

Term of patent 14 years

Int. Cl. D16—03, 04

U.S. Cl. D61—1

FIG. 1.

FIG. 4.

FIG. 3.

FIG. 2.

FIG. 1 is a perspective view of the viewer;
FIG. 2 is a front elevation thereof;
FIG. 3 is a side elevation thereof; and
FIG. 4 is a plan view thereof.
The side opposite to that shown in FIG. 3 is substantially identical to that shown in FIG. 3.

We claim:

The ornamental design for a viewer, substantially as shown and described.
